WALTER L. GOODWIN AND AXEL HOLMAN, OF SEATTLE, WASHINGTON.

DUMP-WAGON BODY.

1,276,345.

Specification of Letters Patent. Patented Aug. 20, 1918.

Application filed November 20, 1916. Serial No. 132,475.

To all whom it may concern:

Be it known that we, WALTER L. GOODWIN and AXEL HOLMAN, citizens of the United States, residing at Seattle, in the county of 5 King and State of Washington, have invented a certain new and useful Improvement in Dump-Wagon Bodies, of which the following is a specification.

Our invention relates to improvements in 10 dump-wagon bodies and the object of our invention is to provide a dump-wagon body in association with the running gear of a vehicle, as an auto-truck, which dump-wagon body shall be specially adapted to 15 serve in the operation of transporting granular material, as, for instance, sand or gravel to dump said material at a desired point or to distribute said material on the path of said vehicle during its travel; and 20 which shall be of such particular plan of construction that several of its parts may be separated and reassembled in the operation of repairing or renewing said parts.

We accomplish this object by devices 25 illustrated in the accompanying drawings wherein Figure 1 is a view in side elevation of one form of a structure embodying our invention; Fig. 2 is a view of the same in cross-section on broken line α , α of Fig. 1; 30 Fig. 3 is a fragmentary view of the same in longitudinal section on broken line γ , γ of Fig. 2; and Fig. 4 is a perspective view of one of the slats.

Referring to the drawings throughout 35 which like reference numerals designate like parts, upon the running gear of a vehicle, represented by wheels 5, axles 6 and supports 7, is mounted a body which includes oppositely disposed side rails 8 and 9 40 of channel iron, which side rails 8 and 9 are re-inforced by wooden rails 10 and 11, respectively, which are disposed to fit tightly within the oppositely facing channels of said side rails 8 and 9 on the top 45 surfaces of which are disposed, to extend lengthwise thereof, bearing bars 12 and 13 and bearing bars 14 and 15, respectively, and on the top surfaces of the bearing bars 12 and 14 are disposed side walls 16 and 17, 50 respectively, which are fastened by bolts, as bolts 18, which extend downwardly through the bearing bars 12 and 13 and side rail 8 on one side of said body, and through bearing bars 14 and 15 and side rail 9 on the 55 other side thereof.

The side rails 8 and 9 are rigidly con-

nected by a front end rail 19 and a rear end rail, indicated by dotted line 20, to form a rectangular body frame, and the side wall 16 and 17 are connected by a front end wall 60 21 and rear end wall indicated by dotted line 22 which end walls 21 and 22 extend therebetween.

At equi-distant points in bearings, like 65 bearings 23 of Fig. 3, formed between the bearing bars 12 and 13 and at corresponding opposite points between the bearing bars 14 and 15, are disposed to be rotatively movable a plurality of shafts 24, each provided on its opposite end portion with journals 70 25 and 26 and with a squared portion 27 adjacent to its journal 25 together with a screw-threaded portion 28 adjacent to said squared portion 27, as shown more clearly 75 in Fig. 4, and that portion of it between said journals 25 and 26 is of rectangular form in cross section.

Securely fastened to each of said shafts 24 by rivets, as rivets 29, is a metal slat, 30, 80 which extends thereon throughout the distance between the journals 25 and 26, and which is so disposed thereon that when the several shafts 24 are mounted in their respective bearings, as shown in Fig. 1, then the forward edge portion of each of said 85 slats 30 shall lap over the rearward edge portion of an adjacent one thereof when all of said shafts 24 shall have been turned to the position indicated in Fig. 3 whereby said slats 30, so long as they are maintained 90 in such position, shall form a floor upon which may be deposited sand, gravel and other like earthy material that is to be transported within said body; but when all of said shafts 24 are rotatively moved to 95 dispose the several slats 30 in the position indicated by dotted lines in Fig. 3, then the material within said body will fall through the spaces between adjacent ones of the several shafts 24 thus to dump the load of material contained in said body. 100

Securely mounted on the outwardly projecting squared portion 27 of each of the shafts 24 is an arm 31, all of which arms 31 are disposed to extend obliquely upward 105 and forward to the positions shown in Fig. 1, when the slats 30 are in their closed positions (as indicated by full lines in Fig. 3), and articulated to the upper end portion of all of said arms 31 is a connecting rod 110 32 whose forward end portion is articulated to a hand lever 33 that is adapted in a well

known manner to be actuated to communicate endwise movements to the connecting rod 32 to swing the arms 31 to dispose and maintain the slats 30 in their open positions 5 shown by dotted lines in Fig. 3, or at any desired angular positions between their open and closed positions, said hand lever 33 being provided with a detent mechanism 34 that is adapted to engage with a notched 10 segment 35 that may be secured to suitable supports not shown.

The operation of a structure embodying our invention may be described as follows: The dump-wagon body being disposed on the 15 running gear of a vehicle, as, for instance, the running gear of an auto-truck, the hand lever 33 is disposed in its forwardmost position shown in Fig. 1, whereby the slats 30 will be in their closed position, as shown 20 in Fig. 3, to form a floor for the body, whereupon sand, gravel or other granular material to be transported is deposited within said body to be supported by the closed slats 30 of said floor during the 25 travel of the vehicle to the point of deposit of its load, at which point the hand lever 33 is moved rearwardly to dispose the slats 30 in their position shown by dotted lines in Fig. 3, thus to permit said granular material to fall through the spaces between adjacent ones of the several slats 30 thereby to unload said material and thereupon 30 the hand lever 33 may be again disposed in its forwardmost position to close the slats 35 30 for another load of material.

If it be desired to distribute material contained within the body over the path of the vehicle while said vehicle is moving thereover, then the hand lever 33 may be moved 40 to such position that its detent mechanism

34 may engage with such one of the notches of the notched segment 35 as will cause the slats 30 to be disposed at such angle as will permit said material to pass downwardly between adjacent ones of them at a desired 45 rate of flow.

If it be required to repair one or more of the slats 30 or the shafts 24 connected therewith such parts may be quickly removed from the structure by disconnecting 50 the connecting rod 32 and removing the bolts 18, whereupon the side walls 16 and 17 and the bearing bars 12 and 14 may be raised and dismounted thus to permit such removal in an obvious manner.

Manifestly, changes may be made in the forms and dimensions of parts of our invention without departing from the spirit thereof.

What we claim is:

In a dump wagon a frame, channel members receiving the side members of the frame, bars superposed upon the channel members, a body having at its sides outstanding flanges, which rests upon the upper 65 bars, securing devices passing transversely through the flanges, bars, channel members and side members of the frame, shafts journaled between the bars, means for turning the shafts simultaneously and slats carried 70 by the shafts and adapted to overlap each other.

In witness whereof, we hereunto subscribe our names this 15th day of November, A. D. 1916.

WALTER L. GOODWIN.
AXEL HOLMAN.
